United States Patent Office

Des. 191,620
Patented Oct. 24, 1961

191,620

TUMBLER

Jack Bloch, Fort Worth, Tex., assignor to Loma Industries, Fort Worth, Tex., a corporation of Texas

Filed Sept. 21, 1960, Ser. No. 62,231

Term of patent 14 years

(Cl. D36—8)

I claim:

The ornamental design for a tumbler, as shown.
